HARRY W. HIBBARD, OF LYNDHURST, OHIO, ASSIGNOR, BY MESNE ASSIGNMENTS, TO HIBBARD CABINETS, INC., OF CLEVELAND, OHIO, A CORPORATION OF DELAWARE

UPRIGHT BEVERAGE-COOLING CABINET

Application filed June 3, 1926. Serial No. 113,410.

The present invention relates to refrigerating cabinets, and more particularly to cabinets of that type which are especially adapted for use in cooling bottled beverages or the like.

Among the objects of the present invention are to provide a bottled beverage refrigerating cabinet which will quickly cool the beverage in such quantities as are ordinarily required by a retail dealer, and in which the bottles are placed so that they are readily accessible when it is desired to withdraw the same.

The invention further contemplates the construction of a cooling cabinet which admits of the bottles of beverage being piled horizontally and chills them from the top of the pile toward the bottom instead of from the bottom toward the top, thereby insuring that the uppermost bottles which are withdrawn for use will be thoroughly chilled.

While one particular embodiment of the invention is shown and described in detail for illustrative purposes, it will be understood that many modifications and changes can be made in the design, proportions and details of construction without departing from the spirit of the invention.

For a full understanding of the invention reference is to be had to the following description and accompanying drawings in which,

Figure 1 is a front elevation of a beverage cooling cabinet which is constructed in accordance with the invention, the doors of the compartment in which the refrigerating machine is mounted being open.

Figure 2 is a vertical longitudinal sectional view through the device.

Figure 3 is a transverse sectional view taken on the line 3—3 of Figure 2.

Figure 4 is a top plan view of the device with the cover removed.

Corresponding and like parts are referred to in the following description and indicated on all of the views of the drawings by like reference characters.

Referring to the drawings, which illustrate one of many possible embodiments of the invention, the reference character A designates

the casing of the cabinet, said casing having a suitable heat insulating construction and being supported above a compartment B in which some conventional form of refrigerating mechanism C is mounted. The front of the compartment is shown as provided with doors 1 which can be swung into an open position, as shown by Figure 1 when it is desired to obtain access to the refrigerating machinery. The cabinet is shown as mounted upon rollers 2, so that it can be easily moved from place to place.

The front of the casing A is formed with an inclined portion which is provided with sliding doors 3. The top portion of the casing A is narrower than the bottom portion thereof and is closed by a removable cover 4. The cover has rabbeted edges 4^a which engage a corresponding seat 5 at the top of the casing and suitable fastening members such as the screws 6 may be utilized for fastening the cover in position.

Arranged within the narrow top portion of the cabinet is a cooling tank 7. This cooling tank rests upon cross bars 8 extending across the cabinet, being secured to the cross bars in some suitable manner as by means of the straps 9 which extend around the top and sides of the tank, the ends of the straps extending through openings in the cross bars and being threaded for engagement with nuts 10. The tank may be filled with brine or any equivalent medium and circulation pipes 11 are arranged within the tank, as shown by Figure 2. The cooling tank is spaced from the end and side walls of the top portion of the casing, and is also spaced from the cover 4, thereby providing for the free circulation of air around all sides thereof.

The space within the casing A and below the cooling tank 7 is subdivided by the upright partitions 12 into a plurality of bottle receiving compartments F. These partitions 12 have a reticulated formation and may be conveniently formed of wire mesh. The partitions 12 at the outer sides of the end bottle receiving compartments F are spaced from the end walls of the casing A, thereby providing upright air circulation passages leading from the bottom of the casing to the top there-

of. The circulation pipes 11 within the cooling tank 7 are connected to pipes 13 which extend downwardly through one of the end air circulation spaces H to the refrigerating machine C which is mounted within the compartment B.

The bottle receiving compartments F are provided with bottom walls 14 which are spaced from the bottom of the casing A, thereby providing an air circulation space J extending along the bottom of the several compartments. The bottom walls 14 have a reticulated formation and may be conveniently formed of wire mesh. These bottom walls 15 are preferably removable and may have the edge portions thereof bent downwardly, as indicated at 14^a, to provide side flanges for supporting the bottom walls in an elevated position above the bottom of the casing when they are arranged in position.

The sliding doors 3 are mounted in channel guides 15 which are provided at the top and bottom of the inclined portion of the front of the casing. There is one of the doors 3 for each of the bottle receiving compartments F. As shown on the drawings there are three of the doors 3, and the two end doors would operate in one guideway, while the intermediate door would operate within another guideway. These doors are provided with flush handles 3^a, so that they can slide freely over each other, and it will be obvious that the sliding door of anyone of the compartments can be opened independently of the sliding doors of the other compartments. Quick access can thus be had to any desired one of the compartments without letting warm air into the other compartments. The bottles, a few of which are indicated at L on Figure 2, are placed in the compartments in a horizontal position, being piled on top of each other in successive layers.

In the operation of the device the contents of the tank 7 are chilled by the refrigerating machine C which may be of any conventional or well known type. The air at the top of the refrigerating compartment A completely surrounds the tank 7 and is in contact with the walls thereof on all sides. This air becomes chilled and the cold air circulates downwardly through the bottles in the bottle receiving compartments F. This cold air comes into contact with the uppermost bottles first so that the top bottles in the various compartments are cooled before the bottom bottles, this being quite a desirable feature because it is the top bottles which are withdrawn first as the supply of bottled beverage is drawn upon by the dealer for use. As the cold air 55 circulates downwardly through the bottles it takes the heat from the bottles and the air becomes warmer as it circulates downwardly. When the air reaches the bottom of the air circulating space J it is several degrees warmer than the air which is in contact with the

cooling tank 7, and this warm air circulates through the bottom space J to the end spaces H and rises through these end circulating spaces H until it reaches the top of the refrigerating casing and again comes in contact with the cooling tank 7. A continuous circulation of the air is thus maintained and this results in a quick and effective cooling of the bottled beverage. It has been found that where there is about three ounces of brine in the tank 7 to each ounce of liquid in the bottles a very rapid cooling of the bottles is possible. Any size, shape or make of bottle can be used, and the bottles are held in position within the refrigerating cabinet so that they are quickly chilled and can be readily withdrawn as they are required to meet the sales of an average retail dealer. The entire cabinet is portable and can be readily moved from place to place and when the cabinet is made of a size to take care of about five cases of bottled goods it will have a capacity which will meet the requirements of the average small dealer.

Having thus described my invention what I claim as new and desire to secure by Letters Patent is,

1. A refrigerating cabinet including a casing having a wide base and a narrow top portion, a cooling tank arranged in the narrow top portion of the casing, transverse partitions extending across the wide base of the casing and subdividing the same into a plurality of elongated compartments in which bottles are adapted to be placed horizontally and endwise, certain of the partitions cooperating with the upright walls of the casing to provide air circulating spaces leading downwardly from the cooling tank.

2. A refrigerating cabinet including a casing having a wide base and a narrow top portion, a cooling tank arranged within the narrow top portion and spaced from the walls of the casing, a plurality of reticulated transverse partitions dividing the wide base portion of the casing into a plurality of elongated bottle receiving compartments in which bottles are adapted to be placed horizontally and endwise, and a reticulated bottom for each compartment which is spaced from the bottom of the casing, the outside transverse partitions of the end compartments being spaced from the ends of the casing to provide air circulating spaces leading downwardly from the cooling tank.

3. A refrigerating cabinet including a casing, a cooling tank at the top of the casing, a plurality of transversely disposed upright partitions arranged under the cooling tank and subdividing the bottom of the casing into a plurality of bottle receiving compartments extending from the front toward the rear, the transverse partitions of the end compartments being spaced from the ends of the casing to provide upright air circulating spaces,

- and reticulated bottom walls for the compartments which are spaced from the bottom of the casing to provide a substantially horizontal air circulating space.
- 5 4. A refrigerating cabinet including a casing, transverse bars extending across the upper portion of the casing, a cooling tank supported on the transverse bars in a spaced relation to the walls of the casing, and upright partitions arranged below the cooling tank in a spaced relation to the ends of the casing and cooperating therewith to provide upright air circulating spaces leading from the bottom of the casing to the top thereof. 70
- 10 5. A refrigerating cabinet including a casing having an open end, transverse bars extending across the upper portion of the casing, a cooling tank resting on the transverse bars and removable through the top of the 75 casing, said cooling tank being spaced from the walls of the casing, a removable cover closing the top of the casing, and upright partitions cooperating with side walls of the casing to provide upright air circulation passageways leading from the bottom of the casing to the top thereof, whereby warm air at the bottom of the casing will circulate upwardly into contact with the cooling tank. 80
- 20 6. A refrigerating cabinet including a casing, a cooling tank at the top of the casing, a plurality of transversely disposed upright partitions arranged under the cooling tank and subdividing the bottom of the casing into a plurality of bottle receiving compartments 85
- 25 extending from the front toward the rear, the casing being provided with an elongated door opening extending across the ends of the several compartments, guide ways at opposite edges of the door opening, and sliding 90 doors mounted within the guide-ways, a door being provided for each compartment and the doors being movable into and out of operative position independently of each other. 95
- 30 7. A refrigerating cabinet including a casing having a wide base and a narrow top portion, the front of the casing having an inclined portion leading from the lower part of the casing to the narrow upper part thereof, a cooling tank mounted in the narrow upper portion of the casing, transversely disposed upright partitions dividing the lower part of the casing into a plurality of compartments extending from the front toward the rear, upper and lower guide-ways at the top 100 and bottom of the inclined portion of the casing, said guide-ways extending across the ends of all of the compartments, and a series of inclined sliding doors mounted upon the before mentioned guide-ways, a door being 105 provided for each compartment and the doors being movable into and out of operative position independently of each other. 110
- 35 8. A refrigerating cabinet including a casing, a horizontally disposed cooling tank extending across the top of the casing and sup- 115
- 40 ported in a spaced relation to the walls of the casing, upright reticulated partitions subdividing the lower portion of the casing into a plurality of compartments extending from the front toward the rear, the outer partitions of the end compartments being spaced from the end walls of the casing to provide air circulating spaces leading from the cooling tank to the bottom of the casing, reticulated bottoms for the various compartments which are supported removably in a spaced relation to the bottom of the casing, the casing being provided with a door opening for each compartment and extending across the ends thereof, and an independent door for each compartment. 120
